UNITED STATES PATENT OFFICE

145,911

DESIGN FOR A COVERED BOWL OR SIMILAR ARTICLE

Lorraine M. Smith, Los Angeles, Calif.

Application December 12, 1945, Serial No. 124,660

Term of patent 7 years

(Cl. D44—15)

To all whom it may concern:

Be it known that I, Lorraine M. Smith, a citizen of the United States, residing at 2922 Oakhurst Ave., Los Angeles 34, in the county of Los Angeles and State of California, have invented a new, original, and ornamental Design for a Covered Bowl or Similar Article, of which the following is a specification, reference being had to the accompanying drawing, forming part thereof.

Fig. 1 is a top plan view of a covered bowl or similar article, with the detachable cover in its normal position, showing my new design; and

Fig. 2 is a perspective view thereof with the detachable cover removed.

I claim:

The ornamental design for a covered bowl or similar article, substantially as shown.

LORRAINE M. SMITH.
